DESIGN FOR A BALANCE TRUING CALIPER

Roy R. While, Chicago, Ill., assignor to Henry Paulson and Company, Chicago, Ill., a copartnership

Application July 21, 1945, Serial No. 120,871

Term of patent 3½ years

(Cl. D52—1)

To all whom it may concern:

Be it known that I, Roy R. While, a citizen of the United States and a resident of Chicago, in the county of Cook and State of Illinois, have invented a new, original, and ornamental Design for a Balance Truing Caliper, of which the following is a specification, reference being had to the accompanying drawing, forming a part thereof, and in which:

Fig. 1 is a perspective view of a balance truing caliper showing my new design;

Fig. 2 is an edge elevational view thereof.

I claim:

The ornamental design for a balance truing caliper, as shown.

ROY R. WHILE.
